CLAIM

The ornamental design for an entry for a bathing tub, as shown and described.

DESCRIPTION

FIG. 1 is a perspective view taken from the top, front and right side of an entry for a bathing tub showing my new design;

FIG. 2 is a top plan view thereof;

FIG. 3 is a front elevational view thereof; and,

FIG. 4 is a right side elevational view thereof, the left side being the mirror image of the right side.

The fragmentary broken line representation of a bathing tub with which the claimed design may be associated is for the purpose of illustration only, and forms no part of the claimed design.
